UNITED STATES PATENT OFFICE.

JOSEPH H. BEHEE, OF LEAVENWORTH, KANSAS.

SCROLL-CUTTING MACHINE.

1,337,428.

Specification of Letters Patent. Patented Apr. 20, 1920.

Application filed August 19, 1918. Serial No. 250,568.

To all whom it may concern:

Be it known that I, JOSEPH H. BEHEE, a citizen of the United States, and a resident of Leavenworth, in the county of Leavenworth and State of Kansas, have invented a certain new and useful Improvement in Scroll-Cutting Machines, of which the following is a specification.

My invention relates to improvements in Scroll Cutting Machines.

It is particularly adapted for cutting the scrolls on the outer end of a violin neck.

The object of my invention is to provide a novel scroll cutting machine by which a scroll may be quickly, accurately and cheaply cut.

A further object of my invention is to provide a scroll cutting machine which is simple in construction, which is strong and durable and not liable to get out of order, and which may be readily operated by an unskilled person.

The novel features of my invention are hereinafter fully described and claimed.

In the accompanying drawings, which illustrate the preferred embodiment of my invention,

Fig. 1 is a side elevation of my improved scroll cutting machine arranged to cut scrolls in a violin neck.

Fig. 2 is a top view of the same, showing the tool supporting member at one limit of its movement, in a lengthwise direction.

Fig. 3 is a view similar to Fig. 2, showing the tool supporting member at the other limit of its lengthwise movement.

Fig. 4 is an enlarged horizontal sectional view, on the line 4—4 of Fig. 1.

Fig. 5 is an enlarged vertical sectional view on the line 5—5 of Fig. 1.

Fig. 6 is a vertical sectional view on the line 6—6 of Fig. 3.

Fig. 7 is a horizontal sectional view on the line 7—7 of Fig. 1.

Similar reference characters designate similar parts in the different views.

1 designates the main frame of the machine, which frame may be of any desired form and material, the frame shown being formed of angle bars folded together.

Rotatably mounted in the frame 1 are two work supporting members comprising respectively two horizontal spur gear wheels 2 and 3, respectively secured to and rotatable with two vertical shafts 4 and 5, each of 55 which is rotatable and vertically slidable in bearings 6 with which the frame 1 at opposite ends is provided.

A tool supporting member comprising preferably a horizontal longitudinal rotary 60 shaft 7 is rotatable and longitudinally slidable in bearings 8 provided in the upper part of the frame 1. The shaft 7 extends radially over the gear wheels 2 and 3 and has its ends disposed respectively adjacent 65 to the centers of said wheels.

9 and 10 designate respectively two circular beveled cutters, the beveled cutting faces of which, preferably converge inwardly.

The two tools comprising the two cutters 9 and 10 are adapted to respectively consecutively cut the two scrolls 11 and 12, Fig. 1, which are at the outer end of a violin neck 13.

For supporting the violin neck 13 on the wheels 2 and 3, so that the cutters 9 and 10 can cut the scrolls 11 and 12, I provide two neck holding devices, as shown in the drawings. These two devices are alike so 80 that a description of one will suffice for both.

I will now describe the neck holding device which is mounted upon the gear wheel 2.

14 designates a block having in its upper side a recess 15, in which is fitted and adapted to be held the neck 13. The block 14 is rigidly secured to the upper side of a plate 16 which is pivoted adjacent to its outer end by a horizontal pin 17 to a base plate 18, which is rigidly secured to the top of 90 the wheel 2.

For clamping the violin neck 13 in the cutting position tightly to the block 14, I provide a horizontal slightly resilient clamping plate 19, Fig. 6, which is mounted upon 95 vertical blocks 20, which are supported by the work supporting gear wheel, to which the blocks are clamped by means of vertical bolts 21, which extend through the clamping plate 19, and are secured at their lower 100

ends to the gear wheel 2 or 3 as the case may be.

For forcing the block 14 and plate 16 upwardly to the operative position, shown in Figs. 1 and 6, with the violin neck 13 held clamped at its upper side against the under side of the spring clamping plate 19, I provide a right-angled lever 22, having one of its arms disposed horizontally and 10 pivotally mounted in a transverse groove 23 which is provided in the upper side of the base plate 18, as shown in Fig. 1. Said arm is provided with a lug 24 extending radially therefrom and adapted to be swung from 15 the operative vertical position, shown in Fig. 1, to a horizontal position, in which latter position, the plate 16 and block 14 may be swung downwardly to bring the neck 13 out of engagement with the clamping plate 19. When the block 14 is in this inclined position, a neck 13 may be placed in or removed from the recess 15. When the neck which is to be cut has been placed in the recess 15, and the lever 22 is swung to 25 the position shown in Figs. 1 and 6, the lug 24, which engages the under side of the plate 16 will force the latter and the block 14 to a position in which the neck 13 will be held tightly clamped against the under 30 side of the clamping plate 19, in which position, the cutter 9 or 10, as the case may be, may be operated to cut the scroll in the side of the neck which is uppermost.

For rotating the shaft 7, it has rigidly 35 secured to it at its center a pulley 25, which is adapted to be driven by a driving belt not shown.

In order that a true scroll may be accurately cut in the violin neck, it is essential 40 that, while the work supporting member, which carries the neck, is being rotated, it shall also be moved parallel with its axis and at the same time the tool supporting member 7 shall be moved transversely to, 45 and preferably, toward, the axis of the work supporting member, and at a changing rate of speed relatively to the constant speed of rotation of the work supporting member.

If in cutting the scroll in the neck, the 50 cutter 9 or 10 is moved toward the axis of the work supporting member, the changing rate of speed of movement of the shaft 7 toward the axis of the work supporting member, should be a diminishing rate of 55 speed.

I will now describe the mechanism by which the shaft 7 and cutting tools 9 and 10 are moved at a diminishing rate of speed alternately in opposite directions simultaneously with the rotation of the wheels 2 and 3, and while the latter are rotating at a uniform rate of speed.

Referring particularly to Figs. 1 and 2, 26 and 27 designate respectively two spur

gear wheels which respectively mesh with 65 the gear wheels 2 and 3 and which are respectively rigidly secured to two vertical shafts 28 and 29 which are rotatable in the frame 1.

In order that the shaft 29 may be manually rotated, it has secured to its upper end 70 a crank 30.

For transmitting rotation from the shaft 29 to the shaft 28, there is provided a chain belt 31 which is mounted upon two sprocket 75 wheels 32 and 33 respectively secured to the shafts 28 and 29.

When the operator turns the crank 30 in a clockwise direction, as viewed in Fig. 2, the gear wheels 2 and 3 will both be turned 80 counter-clockwise by means of the mechanism just above described.

For moving the shaft 7 endwise, when the crank 30 is turned, the shaft 29 has secured to it a bevel gear wheel 34, Fig. 1, which 85 meshes with a bevel gear wheel 35, which is secured to one end of a horizontal longitudinal worm shaft 36 which is rotatably mounted in horizontal arms 37 of a plate 38, which is secured to and supported by the main 90 frame 1. The worm 39 of the worm shaft 36 meshes with two horizontal worm wheels 40 and 41, which are rotatably mounted on a bracket 42 which is secured to and supported by the plate 38.

The worm wheels 40 and 41 are respectively provided with crank pins 43 and 44 which are adapted to respectively releasably and slidably engage two pairs of parallel radial arms 45 and 46 with which two collars 47 and 48 are respectively provided.

The collars 47 and 48 are pivotally mounted on a horizontal longitudinally slidable bar 49, which is parallel with the shaft 7 and which is longitudinally slidable in the 105 bracket 42.

Between the collars 47 and 48 on the bar 49 is a collar 50, having a laterally extending bifurcated arm 51, which is mounted in a peripheral annular groove 52 provided in 110 the pulley 25.

For holding the collars 47, 48 and 50 from longitudinal movement on the bar 49, said bar is provided with two transverse pins 53 and 54, between which said collars are 115 mounted and against which the collars 47 and 48 are adapted to have their outer ends respectively engage.

By swinging the collars 47 and 48 on the bar 49, the arms 45 and 46 may be made to 120 independently engage or disengage with the crank pins 43 and 44.

When the crank 30 is turned clockwise, as viewed in Fig. 2, the worm wheels 40 and 41 will also be turned clockwise by 125 means of the shaft 29, bevel gears 34 and 35 and worm shaft 36. The crank pin 43 engaging with the arms 45 will force the

collar 47 and with it the collars 48 and 50 and bar 49 to the right, as viewed in Fig. 2, thereby moving the shaft 7 and cutting tool 10 to the right, by means of the pulley 5 and arm 51.

As the pin 43 moves from the position shown in Fig. 2, to that shown in Fig. 3, it will move the collar 47, and therefore, the shaft 7 and cutting tool 10 to the right at a constantly diminishing rate of speed, if the worm wheel 40 is moved at a uniform rate of speed.

If a violin neck be inserted in the recess 15, of the block 14, with the parts as shown in Fig. 2, and the crank 30 is turned clockwise, the wheel 3 carrying the violin neck will be revolved, and the crank pin 43 will cause the cutter 10 to cut a spiral in the upper side of the violin neck, the spiral being of volute form with convolutions decreasing toward the center in width, due to the diminishing rate of speed, at which the shaft 7 and cutter 10 is moved to the right.

When the crank pin 43 has moved from the position shown in Fig. 2 to that shown in Fig. 3, the wheels 2 and 3 will have turned nearly two revolutions to the positions shown in Fig. 3. The violin neck which has had the scroll 12 cut in it while carried on the wheel 3, is then removed from the block 14 on said wheel and is placed in the recess 15 of the block 14 which is carried by the wheel 2, the position of the block being reversed, that is with the side having the scroll 12 underneath.

The collar 47 is then swung out of engagement with the pin 43 and the collar 48 is swung so that its arms 46 engage the pin 44.

The lever 22 on the wheel 2 is then swung so as to clamp the violin neck against the clamping plate 19, as shown in Fig. 1.

The crank 30 is then turned in a counter-clockwise direction, thus turning the worm wheels 40 and 41 counter-clockwise, and turning the gear wheels 2 and 3 clockwise.

By the time the pins 44 and 43 have turned to the position shown in Fig. 2, from the position shown in Fig. 3, the shaft 7 and cutter 9 will have been moved to the left, so as to complete the cutting of the scroll 11 in the upper side of the violin neck, carried on the wheel 2.

In order that the scrolls 11 and 12 may have the helical form and opposite inclinations, as the scrolls such as are ordinarily provided on violin necks, I provide means by which the wheels 2 and 3 are moved parallel with their axes different distances in opposite directions during each revolution of said wheels. For this purpose, each of the wheels 2 and 3 has secured to its under side a volute cam 55, Fig. 4 and Fig. 5, the under side of which is provided

with a spiral, and helical, cam face 56 having two convolutions of volute form, each convolution rising and then falling, but not falling as much as it has risen during the complete turn. This form of volute cam imparts the proper vertical movement of the work supporting members, so that the scrolls 11 and 12 will have the proper pitch. By arranging the blocks 14 on the two wheels 2 and 3, as shown, the scrolls 11 and 12 are properly related to each other.

Mounted on the frame 1 are two brackets 57 having arms 58 extending outwardly and radially relatively to the wheels 2 and 3. Respectively rotatably and longitudinally slidably mounted on the arms 58 respectively are two rollers 59 respectively adapted to travel along the cam faces 56 for supporting the cams 55 respectively.

Each roller 59 is provided with a peripheral flange 60 adapted to bear against the outside of the convolution of the cam along which it is traveling. A coil spring 61 encircles each arm 58 and has its ends bearing respectively against the adjacent bracket 57 and adjacent roller 59, thereby holding the roller against its cam, but permitting the roller to move outwardly as it reaches portions of the cam of increasing diameter.

As shown in Fig. 1, the wheel 3, in the initial position is at its highest point. As the scroll is being cut the wheel gradually lowers, owing to the roller traveling along the cam face 56, until the wheel 3 reaches the lowermost position, such as has been reached by the wheel 2 in Fig. 1. At this time the scroll will have been cut in the neck 13. The neck is then removed from the block 14 on the wheel 3 and placed in the block 14 on the wheel 2, and clamped in position on said wheel by the means already described.

The crank 30 is then turned counter clockwise, thus turning the wheel 2 clockwise about two revolutions, when the parts will reach the position shown in Fig. 2, and the scroll 11 will have been cut in the other side of the neck, the latter having been reversed in position, as has already been stated; when it is transferred from the wheel 3 to the wheel 2.

To stop the wheels 2 and 3 at the proper places, each of the cams 55 may have a stop pin 62 in the outer convolution against which the roller 59 will strike.

For steadyng the plate 16 against lateral movement, it may be slidably fitted between two vertical arms 63 on the plate 18.

For holding the shaft 7 from springing upwardly, the frame 1 is provided, preferably with a longitudinal brace plate 64 having bearing portions 65 adapted to bear against the upper side of the shaft 7 respectively adjacent to the cutters 9 and 10.

In the operation of the invention, the violin neck blank is first inserted in the block 14 on the wheel 3, the parts being as shown in Fig. 2. The crank 30 is then turned clockwise until the wheels 2 and 3 have turned nearly two complete revolutions to the position shown in Fig. 3. The scroll 12 will then have been cut in one side of the neck. The latter is then inserted scroll side down in the block 14 on the wheel 2, following which, after the neck has been clamped in position, the crank 30 is turned counter clockwise nearly two revolutions, or to the original position shown in Fig. 2, at which time, the cutter 9 will have cut the scroll 11 in the other side of the violin neck. The neck is then removed and another neck is placed in the block 14 on the wheel 3, following which the above operation is repeated.

I do not limit my invention to the structure shown and described, as modifications, within the scope of the appended claims, may be made without departing from the spirit of my invention.

What I claim is:—

1. In a scroll cutting machine, a tool supporting member, a work supporting member, means for rotating the work supporting member and for simultaneously moving the other member at a diminishing rate of speed transversely to the axis of the rotatable member, and means for moving one of said members parallel with the axis of the rotatable member simultaneously with the rotation of the latter.

2. In a scroll cutting machine, a tool supporting member, a work supporting member, means for simultaneously rotating the work supporting member and moving the other member at a changing rate of speed transversely to the axis of the rotatable member, and means for moving one of said members parallel with the axis of the rotatable member simultaneously with the rotation of the latter.

3. In a scroll cutting machine, a tool supporting member, a work supporting member, means for rotating the work supporting member and simultaneously moving the other member transversely to the axis of the rotatable member, and means for moving one of said members alternately different distances in opposite directions parallel with the axis of the rotatable member during one revolution of the latter.

4. In a scroll cutting machine, a tool supporting member, a work supporting member, means for rotating the work supporting member and simultaneously moving the other member transversely to the axis of the rotatable member, and means for moving one of said members alternately different distances in opposite directions parallel

with the axis of the rotatable member during each of a plurality of revolutions of the latter.

5. In a scroll cutting machine, a tool supporting member, a work supporting member, means for rotating the work supporting member and simultaneously moving the other member at a changing rate of speed transversely to the axis of the rotatable member, and means for moving one of said members alternately in opposite directions parallel with the axis of the rotatable member during one revolution of the latter.

6. In a scroll cutting machine, a tool supporting member, a work supporting member, means for rotating the work supporting member and simultaneously moving the other member at a changing rate of speed transversely to the axis of the rotatable member, and means for moving one of said members alternately different distances in opposite directions parallel with the axis of the rotatable member during one revolution of the latter.

7. In a scroll cutting machine, a work supporting member, a rotary tool supporting shaft, means for rotating said member and simultaneously moving the shaft at a changing rate of speed transversely to the axis of said member, and means for moving the work supporting member alternately in opposite directions parallel with its axis and during a revolution of said member.

8. In a scroll cutting machine, a work supporting member, a rotary tool supporting shaft, means for rotating said member and simultaneously moving the shaft at a changing rate of speed transversely to the axis of said member, and means for moving the work supporting member alternately different distances in opposite directions parallel with its axis and during a revolution of said member.

9. In a scroll cutting machine, a tool supporting member, two work supporting members each having means for holding a violin neck in position for being cut by a tool carried by the tool supporting member, and means for rotating the work supporting members and simultaneously moving the tool supporting member transversely to the axes of the work supporting members.

10. In a scroll cutting machine, a tool supporting member, two work supporting members each having means for holding a violin neck in position for being cut by a tool carried by the tool supporting member, and means for rotating the work supporting members and simultaneously moving the tool supporting member at a changing rate of speed alternately in opposite directions transversely to the axes of the work supporting members.

11. In a scroll cutting machine, a tool sup-

- porting member, two work supporting members each having means for holding a violin neck in position for being cut with a tool carried by the tool supporting member, and 5 means for moving the tool supporting member at a changing rate of speed transversely to the axes of the work supporting members and simultaneously rotating the work supporting members.
- 10 12. In a scroll cutting machine, a tool supporting member, two work supporting members each having means for holding a violin neck in position for being cut with a tool carried by the tool supporting member, and 15 means for rotating said work supporting members and simultaneously moving the tool supporting member at a diminishing rate of speed alternately in opposite directions transversely to the axes of the work 20 supporting members.
13. In a scroll cutting machine, a tool supporting member, two work supporting members each having means for holding a violin neck in position for being cut by a tool carried by the tool supporting member, means for rotating the work supporting members and simultaneously moving the tool supporting member transversely to the axes of the work supporting members, and 25 30 means for moving the latter parallel with their axes simultaneously with their rotation.
14. In a scroll cutting machine, a tool supporting member, two work supporting members, each having means for holding a violin neck in position for being cut by a tool carried by the tool supporting member, means for rotating the work supporting members and simultaneously moving the tool supporting member at a changing rate of speed alternately in opposite directions transversely to the axes of the work supporting members, and means for moving the work supporting members parallel with 40 45 their axes during their rotation.
15. In a scroll cutting machine, a tool supporting member, two work supporting members, each having means for holding a violin neck in position for being cut by a tool carried by the tool supporting member, means for rotating the work supporting members and simultaneously moving the tool supporting member at a diminishing rate of speed alternately in opposite directions transversely to the axes of the work supporting members, and means for moving the work supporting members parallel with 50 55 their axes during their rotation.
16. In a scroll cutting machine, a tool supporting member, two work supporting members, two revolute members, means for simultaneously rotating said revolute members and said work supporting members, and means adapted to consecutively engage 60
- said revolute members for alternately moving the tool supporting member in opposite directions transversely to the axes of the work supporting members and at a changing rate of speed. 65
17. In a scroll cutting machine, a tool supporting member, two work supporting members, a rotatable worm, two worm wheels meshing with said worm, means for simultaneously rotating said worm and said work supporting members, and means actuated by said worm wheels for alternately moving the tool supporting member in opposite directions transversely to the axes of the work supporting members and at a changing rate of speed. 70 75
18. In a scroll cutting machine, a tool supporting member, two work supporting members, two revolute members each having a crank pin, means for simultaneously rotating the work supporting members and said revolute members, and means adapted to alternately engage said crank pins for alternately moving said tool supporting member in opposite directions transversely to the axes of said work supporting members. 80 85 90
19. In a scroll cutting machine, two revolute members, each having a crank pin, means for revolving said revolute members, a tool supporting member, a reciprocative member, means by which the tool supporting member moves conjointly with said reciprocative member, and means adapted to alternately engage said crank pins for reciprocating said reciprocative member at a changing rate of speed. 95 100
20. In a scroll cutting machine, a tool supporting member, a reciprocative bar, means for moving the tool supporting member conjointly with said bar, a revolute member having a crank pin, means for revolving said revolute member, and means movable with said bar and by said crank pin for moving the bar at a changing rate of speed while the revolute member is revolving at an even rate of speed. 110
21. In a scroll cutting machine, a tool supporting member, a reciprocative bar, means connecting said bar and said member by which they move conjointly, two revolute members, each having a crank pin, two connecting members movable with said bar and movable respectively into and out of driving engagement with said crank pins; and means for revolving said revolute members. 115 120
22. In a scroll cutting machine, a tool supporting member, a reciprocative bar, two revolute members, each having a crank pin, means connecting said bar and said member by which they move conjointly, two connecting members pivoted to and movable with said bar and movable respectively into and 125

out of driving engagement with said crank pins, and means for revolving said revolute members.

23. In a scroll cutting machine, a tool supporting member, a rotary work supporting member, a support for a violin neck pivoted to said work supporting member, a clamping member carried by said work supporting member, and a lever for swinging said support into operative position relatively to said tool supporting member and in said position holding the violin neck against said clamping member.

24. In a scroll cutting machine, a rotary work supporting member having means for

holding a violin neck, a volute cam attached to and adapted to move the work supporting member parallel with the axis of the latter, a roller engaging and adapted to move said cam, supporting means on which the roller is mounted and movable radially with respect to the axis of said work supporting member, and a tool supporting member movable transversely to the axis of said member, and connections between said members by which they are simultaneously operated.

In testimony whereof I have signed my name to this specification.

JOSEPH H. BEHEE.
